No. 869,217.

PATENTED OCT. 22, 1907.

F. STRATTON.
ROLLER BEARING.
APPLICATION FILED DEO. 10, 1906.

UNITED STATES PATENT OFFICE.

FRANKLIN STRATTON, OF PROVIDENCE, RHODE ISLAND.

ROLLER-BEARING.

No. 869,217.

Specification of Letters Patent.

Patented Oct. 22, 1907.

Application filed December 10, 1906. Serial No. 347,173.

To all whom it may concern:

Be it known that I, FRANKLIN STRATTON, a citizen of the United States, residing at Providence, in the county of Providence and State of Rhode Island, have 5 invented certain new and useful Improvements in Roller-Bearings, of which the following is a specification.

This invention relates to an anti-friction bearing, and more particularly to a roller-bearing having its rollers 10 journaled in connected bearing-rings whereby a complete cage-like roller-device is formed which can be easily applied to a bearing or removed therefrom without disassembling the parts thereof.

The object of my invention is the production of a 15 cheap and simple roller-bearing having few parts, one which is strong, durable, easily applied and removed, which assures a smooth and even motion to the revolving part having contact therewith; and in which binding and uneven wear is entirely prevented.

20 To this end the invention consists in the construction, arrangement, and combination of parts to be hereinafter described and particularly pointed out in the subjoined claims.

Referring to the drawings, like numerals of reference 25 refer to like parts in the several figures.

Figure 1 is a side elevation of my improved bearing applied to a shaft or axle. Fig. 2 is a cross-section taken on line $y-y$, Fig. 1. Fig. 3 is an enlarged central vertical section of the roller-bearing. Fig. 4 is an inner 30 side view of one of the annular roller-supports. Fig. 5 is a section taken on line $z-z$, Fig. 4, looking in the direction of the arrow crossing said line. Fig. 6 is an elevation of one of the solid bearing-rollers. Fig. 7 is an elevation of one of the spacing-rollers. Fig. 8 is a longitudinal section of one of the hollow bearing-rollers. Fig. 9 is an elevation of one of the tie-rods around which the hollow bearing-rollers revolve.

The numeral 1 designates a shaft or axle to which my improved roller-bearing 2 is applied. Obviously, the 40 shaft may revolve within the roller-bearing and the whole held within a box, or the shaft may be stationary and an object, such as a wheel or the like, revolve on the roller bearing.

My improved bearing comprises two bearing-rings 3 45 which are exact counterparts, an annular series of bearing-rollers comprising solid rollers 4 and hollow rollers 4^a, which are spaced equidistantly around the bearing-rings, and spacing-rollers 5 interposed between the bearing-rollers and in contact therewith. The bearing- 50 rings are of a width somewhat greater than the diameter of the spacing-rollers but narrower than the bearing-rollers, and each ring has its inner face provided with sockets or depressions 6 open at the edges of the ring and apertures 7 central of said sockets. Between said 55 sockets or depressions are arranged sockets or depressions 8 which are circular in formation and smaller than

the sockets 6 but preferably of the same depth; each having an aperture 9 arranged central thereof. The diameters of the sockets or depressions 8 are smaller than the width of the bearing-rings and are therefore closed 60 at the edges of said rings. Attention is directed to the fact that the confining walls of the sockets or depressions 6 are in arcs of circles and that the distance between the axes of two adjoining sockets or depressions 6 and 8 is less than the combined radii of said sockets so 65 that they communicate at 10. Two or more of the apertures 9 are countersunk on the outer faces of the bearing-rings, as at 11, three such apertures being shown in the drawings.

At points where the countersink apertures are located, the hollow bearing-rollers 4^a are located, as clearly shown at 12, in Figs. 2 and 3. Through said hollow bearing-rollers, tie-rods 13 are passed which have their ends reduced, as at 14 to form shoulders 15, the reduced ends fitting the countersink apertures in 70 the bearing-rings and the shoulders bearing against the inner socketed sides of said rings. Said tie-rods have their ends countersunk into the countersink apertures 9 so that they properly space and securely connect the bearing-rings. This assures a free motion to the hollow 75 bearing-rollers, which have their ends fitting into the sockets 6 through which tie-rods are passed and in which said bearing-rollers are centered to insure free action around said rods. The remaining bearing-rollers are solid and provided at their ends with 80 gudgeons 16 which enter the apertures 7; the ends of the body portions 17 of the bearing-rollers fit into the sockets or depressions 6 and are beveled at 18 to reduce to a minimum the frictional contact thereof with the inner 85 walls of said sockets. The ends of the hollow bearing-rollers are similarly beveled, as at 19, for the same purpose. It is to be noted that the degree of bevel at the ends of the bearing-rollers is less than the depth of the 90 sockets in which they are seated, so that the cylindrical extremities of the body portion of said rollers are confined within the walls of said sockets, this assuring proper retention and centering of the rollers within 95 said sockets. By reason of the bearing-rollers being larger in diameter than the width of the bearing-rings, the circumferential faces extend beyond the edges of 100 the latter and are free to contact against surrounding and confined parts, without said parts coming in contact with any other portion of this improved roller-bearing.

The spacing-rollers located between the bearing-rollers are also provided at their ends with gudgeons 20 which fit into the apertures 9 in the bearing-rings, and the ends of the body-portions 21 of the spacing-rollers fit into the sockets or depressions 8 in said rings and are beveled at 22 to reduce to a minimum the frictional 105 contact thereof against the inner walls of said sockets or depressions. As clearly shown in Figs. 2 and 3, the 110

body of each spacing-roller is in contact throughout its length with two adjoining bearing-rollers, which prevents deflection of the latter and takes all strain off the gudgeons of the same. The cylindrical extremities of the body portions of said spacing-rollers are confined within the walls of the sockets 8 similar to the bearing-rollers and for similar purpose.

By means of this construction most of the bearing-rollers can be made solid, as it requires only three tie-rods to securely connect the bearing-rings in a rigid manner. This greatly simplifies the construction and assures a free acting bearing.

It is not my intention to confine this invention to a cylindrical roller-bearing, as all the novel features of 15 the same may be embodied in a thrust-bearing which is common in the art and in which two bearing-rings of different sizes are employed with the bearing-rollers arranged radially between said bearing-rings. The following claims are therefore to be construed without 20 regard to the exact disposition and arrangement of the rollers and bearing-rings, except where in the claims, the disposition and arrangement is specifically recited.

Having thus described my invention, what I claim is,—

- 25 1. A roller-bearing comprising an annular series of rollers having gudgeons at opposite ends, connected supports at opposite ends of said rollers having sockets to receive the ends of said rollers and apertures to receive said gudgeons.
- 30 2. A roller-bearing comprising an annular series of rollers, part of which are solid and have gudgeons at opposite ends and part of which are hollow, bearing-rings at opposite ends of said rollers having sockets in their inner surfaces and apertures extending therethrough central of said 35 sockets, the ends of said rollers being seated in said sockets and the gudgeons of the solid rollers fitting their respective apertures, and tie rods passed through said hollow-rollers and entering the corresponding apertures in the bearing-rings to tie the latter together.
- 40 3. A roller-bearing comprising bearing-rings having each a series of sockets open at the inner and outer edges of

said rings, and sockets of smaller size between said first mentioned sockets and opening into the latter at opposite points, bearing-rollers having their ends fitting into said first mentioned sockets and their circumferential surfaces 45 extending beyond the edges of said bearing-rings, spacing-rollers having their ends fitting into said smaller sockets and in contact throughout their length with said bearing-rollers, and means for connecting said bearing-rings.

4. A roller-bearing comprising two bearing-rings having 50 each an annular series of sockets open at the edges of the rings, sockets of smaller size between said first mentioned sockets, each of said smaller sockets being closed at the edges of the bearing-rings but opening at opposite points into two of the first mentioned sockets, and apertures 55 through said bearing-rings central of said sockets, an annular series of bearing-rollers having their circumferential surfaces extending beyond the edges of said bearing-rings, part of said rollers being solid and having gudgeons at opposite ends and part thereof being hollow, said bearing-rollers having their ends fitting said first mentioned sockets and the solid bearing rollers having their gudgeons fitting their respective apertures in the bearing-rings, tie-rods passed through the hollow bearing-rollers and having their ends secured in the corresponding apertures in said 65 bearing-rings, and spacing-rollers between the bearing-rollers and in contact therewith, said spacing-rollers having gudgeons at their ends fitting into the apertures in the smaller sockets and having their ends fitting into the last mentioned sockets.

5. A roller-bearing comprising an annular series of rollers part of which are solid and part hollow, supports at opposite ends of said rollers having sockets to receive the ends of the latter and apertures central of the sockets receiving the hollow rollers, and tie-rods passed through 75 the hollow rollers and having opposite ends reduced to form shoulders; said tie-rods having their shoulders bearing against the inner walls of the apertured sockets, their reduced ends passed through said apertures, and the extremities of said reduced ends arranged to secure the said 80 supports to said tie-rods.

In testimony whereof, I have affixed my signature in the presence of two subscribing witnesses.

FRANKLIN STRATTON.
